THERAPEUTIC APPARATUS

Filed March 14, 1958

A cross-sectional view of a cylindrical device. The central vertical component is labeled 13. A horizontal tube labeled 12 passes through it. Two horizontal plates labeled 14 are attached to the sides of the central component. A U-shaped base is labeled 26, with a central vertical tube labeled 28. A curved tube labeled 21 is attached to the top of the central component. A curved tube labeled 25 is attached to the bottom of the base. Various other numbers are scattered around the diagram, including 20, 22, 23, 24, 25, 26, 27, and 28.

THERAPEUTIC APPARATUS

Jozef Nawara, Chicago, Ill.

Application March 14, 1958, Serial No. 721,509

1 Claim. (Cl. 272—58)

This is the continuation-in-part of the pending application for a therapeutic apparatus, Serial No. 714,565 filed February 11, 1958.

As far as applicable the objects of the invention specified in the said pending application are identical with the objects of the present disclosure.

Specifically, the principal object of the present invention is the provision, in connection with an angularly shiftable platform which supports a patient in a recumbent position, of adjustable stop members at the ends of the platform for preventing sliding of a patient's body in a longitudinal relation with the platform while the latter makes teeter or seesaw motions.

Another object of the present invention is the provision of a pair of stop members, one at each end of the platform, one stop member engaging the patient's feet and the other stop member engaging a patient's head, the two stop members being provided with suitable mechanism for adjustably interlocking the stop members with the platform in conformity with the patient's height while the patient remains in a recumbent position upon the platform.

A still further object of the present invention is the provision of a suitable mechanism whereby the said stop members may be adjusted on a vertical plane with relation to the platform.

A still further object of the present invention is the provision of a suitable pivotal connecting means for the stop member aforesaid whereby the stop member may be angularly shifted with relation to the platform and used as a cushion for supporting a patient's head when the platform is used as an examining table.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application, and in which like designating characters refer to corresponding parts throughout the several views:

Fig. 1 is a side elevational view of a platform, with a stop member supported thereon at each end of the platform in a longitudinal as well as vertical adjustable relation with the platform, further illustrating a support disposed below the platform in a longitudinal central relation therewith, with the pivotal connecting means between the platform and the support whereby the platform may be capable of making teeter or seesaw motions upon said pivotal connecting means, further illustrating a superstructure disposed above the platform for supporting a suitable mechanism operable by the patient while on the platform, for alternately shifting the ends of the platform on a vertical plane for thereby imparting a seesaw motion to the platform upon said pivotal connecting means;

Fig. 2 is an enlarged fragmentary top elevational view of the platform and of the stop member in an operative position therewith; and

2

Fig. 3 is an end elevational view of the platform with a rear side elevational view of the stop member when the latter remains in an operative position with the platform.

5 Referring to the present drawing in detail there is shown therein an oblong platform 10. In a spaced relation with the edges of said platform 10 is a rectangular tubular frame, which includes a pair of side rails 11 and a pair of end rails 12. Rigidly affixed to the underface 10 of platform 10 is a plurality of plates 13. The outer ends of said plates 13 extend beyond the edges of platform 10, and are directed upwardly, and there terminate in spoon-like members 14, defining cradles within which the rails 11 and 12 of the frame are received and upon 15 which the same rest. Said members 14 may be welded or otherwise rigidly affixed to said rails 11 and 12 for maintaining the frame in a rigid spaced relation with the edge of platform 10, as is best seen in Fig. 2.

Supported in an adjustable vertical and longitudinal relation with platform 10, at each end of the latter, are foot and head stops, generally indicated by 15 in Fig. 1, for supporting feet and head of the patient for preventing sliding of the patient longitudinally of platform 10 when a patient remains in a supine position upon the platform 25 and as the latter makes seesaw motions upon its pivot as will be later described.

Each of said stops 15 includes backing 16, made of stiff material, to which cushion 17 is affixed in any suitable manner. Cushions 17 in a pair of said stops 15 are 30 disposed toward each other, as is seen in Fig. 1.

Hinge loop 18 is affixed to backing 16 through the medium of lateral flanges 19 extending from loop 18, and screws 20 or like fasteners, which are passed through said flanges 19 and which engage said backing 16.

35 Journalled within loop 18 is the central portion of the U-shaped bar 21. Each stop 15, including backing 16 and cushion 17, may be angularly shifted with said loop 18 upon said central portion of said U-shaped bar 21 for the purpose of optionally bringing cushion 17 40 either to a substantially vertical position with relation to platform 10, as shown in Fig. 1, or to a horizontal position. When in a vertical position cushion 17 and its backing 16 function as a stop for the purpose already mentioned, and when in a horizontal position cushion 17 45 may be used as a pillow or rest for supporting the patient's head. Screw 22 passed through said loop 18, bearing against the said central portion of said U-shaped bar 21 interlocks the two, for maintaining stop 15 in its rigid adjusted relation with said bar 21.

50 The ends of said U-shaped bar 21 are bent to define lateral extensions 23. The latter are bent in a downward perpendicular relation to define vertical extensions 24.

Means for supporting said stops 15 in a longitudinal 55 adjustable relation with platform 10 includes a pair of tubular members 25, a pair of which for each of said stops 15 is mounted upon the side rails 11 for longitudinal sliding movement thereon. Each of said tubular members 25, adjacent the end thereof which is proximate to the end of platform 10, is provided with an adjusting screw 26, passed through the body of each of said tubular members 25, and bears against said side rails 11 for maintaining said tubular members 25 in their rigid adjusted relation therewith.

60 Formed at the opposite end of each of said tubular members 25 is a vertical tubular member 27, within which said vertical extensions are receivable and wherein the latter may be adjusted vertically for bringing said stops 15 toward or away from platform 10. Screws 28 65 passed through said vertical tubular members 27 are adapted to engage and bear against said vertical extensions 24 for maintaining the latter in their vertical ad-

justed relation with said vertical tubular members 27. Thus, said stops 15 are adjustable longitudinally of platform 10, conforming to the height of a patient reposing upon platform 10, as well as in a vertical relation with said platform 10.

The support disposed below platform 10 in a substantially longitudinally central relation therewith, includes beam 29 positioned in a transverse relation with platform 10. Said beam 29 is of a substantially frustoconical shape on a transverse cross section, with its narrower end disposed in proximity of platform 10. Affixed to each end of said beam 29 by means of a plurality of bolts or like fasteners 30, is a sheathing plate 31, in an enveloping relation with the sides and the upper end of said beam 29, said bolts 30 being passed through the side portions of said plates 31 and the sides of said beam 29.

Affixed to each side of beam 29, by means of screws, bolts or like fasteners 32, is a pair of leg supporting plates 33, one adjacent the inner edge of the side of each of said sheathing plates 31. The flattened upper portion 34 of the upper tubular leg portion 35 is affixed to each of said plates 33 by means of screws, bolts or like fasteners 36. Thus there are four of said upper tubular leg portions 35, a pair on each side of beam 29 in a downwardly spreading relation with the opposed pair of said tubular leg portions 35 affixed to the opposite side of said beam 29, as is seen in Figs. 1 and 3.

Receivable through the lower open end of each of said tubular leg portions 35 is a cylindrical lower leg portion 37, in a telescopically adjustable relation. Screws 38 passed through the lower ends of said upper tubular leg portions 35, engaging said lower leg portions 37 maintain the two leg portions in their vertically adjusted relation, for thereby maintaining platform 10 in its adjusted distanced relation with the floor. Casters 39 carried by the lower ends of said cylindrical lower portions 37 of the legs support the legs upon the floor.

Welded or otherwise rigidly affixed to the intermediate upper portion of each of said sheathing plates 31 is a cylindrical bearing 40, the outer end of which is sealed by the end plate 41, which is provided with a diametrical slot for receiving therewithin tongue 42 formed at each end of cylindrical shaft 43. By virtue of this arrangement shaft 43 is rigidly interconnected with beam 29 and remains immovable with relation thereto. Journalled for a rotary movement upon said shaft 43 is a tubular hinge member 44 which is interposed between the inner ends of said cylindrical bearings 40. Said hinge member 44 is welded or otherwise rigidly affixed to the underface of said platform 10 in a transverse longitudinally central relation therewith. By virtue of this arrangement said tubular hinge member 44 permits teeter or seesaw motion of platform 10 upon shaft 43 when the ends of platform 10 are caused to alternately angularly shift in upward and downward directions.

Braces 45 interconnect the four legs forming the support for platform 10.

Each upper tubular leg portion 35 is provided with a downwardly directed hook 46, which is engaged by the lower end of coil spring 47.

On each side of pivot 43—44 there is a pair of downwardly depending plates 48 affixed to the underface of platform 10, each plate 48 being provided with a row of apertures 49, with one of which the upper end of coil spring 47 is capable of selective engagement. By virtue of this arrangement coil springs 47 exert pulling action upon platform 10 adjacent each end of the latter for the purpose of normally tending to shift platform 10 to a horizontal position. The engagement of upper ends of springs 47 on each side of pivot 43—44 may be varied to conform to a patient's weight at each end of platform 10.

Downwardly depending from each end of platform 10 is a telescopically extensible stop member, generally indi-

cated by 50 in Fig. 1, composed of a plurality of telescopically interconnected parts 51, 52 and 53, which are interconnected by screws 54 for the purpose of maintaining said parts in their extended adjusted relation toward or away from the floor. The lowermost part 51 of stop member 50 at each end of platform 10 coming in contact with the floor limits the downward shifting movement of that end of platform 10 toward the floor. One of said stop members 50 may be extended farther toward the floor than the other of said stop members 50, thereby permitting one end of the platform to shift farther away from the floor than the other end of the platform, depending upon the particular therapeutic requirements of any given patient. Optionally both of said stop members 50 may be extended in contact with the floor thereby preventing the seesaw motion of the platform. In this last instance the platform would be rendered immovable and may then be used as an examining table.

The superstructure aforesaid includes a substantially rectangular frame 55, which is supported by four legs 56, including a telescopically extensible member 57, the lower end of which carries caster 58. Said extensible member 57 may be rigidly affixed to the upper portion of leg 56 by means of screw or like fastener 59 for maintaining the leg in its rigid adjusted relation for supporting frame 55 in any selected distance from platform 10. Brace 60 connects the upper end of each leg 56 with the longitudinal side member of frame 55 for further supporting said frame 55 upon said legs 56.

One or more rods 61 disposed within the pair of the side members of frame 55, in a longitudinal spaced relation, and rigidly connected with the end members of said frame 55, support one or more sleeves 62 in a sliding relation, adjustable upon rod 61 in a rigid relation by means of screw 63.

Said sleeve 62 is provided with a downwardly depending hook 64 for removably supporting thereon rod 65, to the lower end of which is connected in a swivelled relation a pulley supporting fixture 68 which carries pulley 67. A cord passed over one or more pulleys 67 is capable of supporting weights, handles and numerous other exercising devices for exercising legs, hands and arms of a patient while reposing upon platform 10.

Supported within frame 55 in a swivelled relation, and centrally thereof, is a pair of pulleys 68. The end members of frame 55 are each supporting pulley 69 in a swivelled relation. Said pulleys 68 and 69 are disposed below the plane of said frame 55.

Passed over one of said end pulleys 69 and one of said central pulleys 68 is cord 70, while passed over the opposite end pulley 69 and the remaining central pulley 68 is cord 71. The ends of said cords 70 and 71 past said central pulleys 68 are connected with stirrups or handles 72, while the opposite ends of said cords 70 and 71, past said end pulleys 69 lead in a downward direction and are disengagably connected with hooks 73 each downwardly depending from each end of platform 10.

When a patient reposing upon platform 10 alternately imparts by his hands a pulling action in a downward direction upon one or the other of said handles 72 the ends of platform 10 will be caused to angularly shift in an upward direction thereby imparting to platform 10 a seesaw motion upon its pivot 43—44, thereby affording exercise to the patient's hands and arms and aiding the blood circulation as the patient's body is subjected to the seesaw motion with the platform.

On disconnecting the ends of cords 70 and 71 from hooks 73 platform 10 may then be shifted with its appurtenances away from said frame 55, casters 39 permitting free rolling upon the floor. When platform 10 has been removed from under frame 55, with stop members 50 extended to an equal length and in contact with the floor, with the several parts 51, 52 and 53 intercon-

nected by screws 54, the platform may then be used as an examining table.

In that latter use of platform 10 stop 15 is capable of angular adjustment from vertical to horizontal by virtue of the pivotal connection of the hinge loop 18 with the central portion of the U-shaped bar 21, and when so adjusted cushion 17 is capable of use as a pillow for supporting the patient's head.

While there are described herein preferred embodiments of the present invention, it is nevertheless to be understood that minor changes may be made therein without departing from the spirit and scope of the invention as claimed.

What I claim as new is:

In a therapeutic apparatus including a pivotally supported platform, means for imparting a seesaw motion to the platform while the latter supports a recumbent patient thereon, and a pair of longitudinal rails in spaced relation with the platform and connected thereto, a pair of stop cushion devices one at each end of the platform for engaging the head and feet of a patient while in recumbent position on the platform, each said device comprising a pair of supporting sleeves slidably adjustable on said rails, a U-shaped bar in transverse relation with the platform and disposed thereabove, downwardly directed

extension at the free ends of said U-shaped bar, tubular members rigidly formed with and extending in a vertically transverse relation with said supporting sleeves, said extensions being receivable within said tubular members and being shiftable therewithin in a vertical direction for adjusting the distance of said bar from said platform, means for interlocking said tubular members with said extensions for maintaining the latter in their adjusted relation with said tubular members, each said device including a cushioned member having a stiff backing and a cushion thereon, the two cushions being disposed in a face-to-face relation, a hinge loop carried by the backing of each cushioned member, said hinge loop being in an encompassing relation with said bar for angularly adjusting said cushioned members upon said bar, and means for interlocking said hinge loop with said bar for maintaining said cushioned member in its angularly adjusted relation with said bar.
